UNITED STATES PATENT OFFICE.

JOHN H. HUMES, OF ST. LOUIS, MISSOURI.

DESIGN FOR A MEMBER OF BELT-FASTENERS.

SPECIFICATION forming part of Design No. 29,698, dated November 22, 1898.

Application filed October 22, 1897. Serial No. 656,105. Term of patent 7 years.

To all whom it may concern:

Be it known that I, JOHN H. HUMES, a citizen of the United States, residing at St. Louis, State of Missouri, have invented and produced a new and original Design for a Member of a Belt-Fastener, of which the following is a specification, reference being had to the accompanying drawing, showing a part thereof.

- The drawing is a perspective view of one member of a belt-fastener, showing my new design.

The leading features of my design consists in a belt-fastener provided with a series of 5 rectangular openings formed in one member of the belt on a line with one another and adjacent to one edge of the same and a series of inclined slots formed in said belt and opening into said openings.

Referring to the drawing, 1 represents one member of the belt; along one edge of which are formed a series of rectangular openings 2, which are located adjacent to one of said belts and on a line with one another. Opening into each of the rectangular openings 2 is an inclined slot 3, all of which are inclined in the same direction.

What I claim is—

The design for a member of a belt-fastener, substantially as herein shown and described.

In testimony whereof I affix my signature in presence of two witnesses.

JOHN H. HUMES.

Witnesses:

ALFRED A. MATHEY,
C. F. KELLER.
